UNITED STATES PATENT OFFICE.

WALTER SCOTT, OF PLAINFIELD, NEW JERSEY, ASSIGNOR TO R. HOE & CO.,
OF NEW YORK, N. Y.

ROTARY PRINTING-MACHINE.

SPECIFICATION forming part of Letters Patent No. 372,712, dated November 8, 1887.

Application filed June 26, 1882. Serial No. 65,174. (No model.)

To all whom it may concern:

Be it known that I, WALTER SCOTT, of Plainfield, in the county of Union and State of New Jersey, have invented an Improvement in Rotary Printing-Machines, of which the following is a specification.

In my present invention the types are upon one half of the main cylinder, and an inking-table occupies the other half of the cylinder. The paper is brought to the impression-cylinder and receives one impression. It is then taken off by a transfer-cylinder, and the tail end of the sheet is taken again by the impression-cylinder, so as to present the plain side of the paper for the second impression. The paper is then folded in half between the impression-cylinder and the transfer-cylinder and by the latter conveyed to a folding apparatus.

This invention is specially applicable to presses where there are four impression-cylinders supplied from two rolls of paper, and four folding-machines; but the features hereinafter more fully described and claimed may be used where only one impression cylinder is provided.

In the drawings, Figure 1 is a vertical section of my improved press, showing one set of devices complete, and indicating the places where the other impression-cylinders are applied, each being supplied with its proper transfer-cylinder and accompanying devices, which in this figure are omitted for greater clearness. Fig. 2 is a section of the impression and transfer cylinders in larger size, and Figs. 3, 4, and 5 are diagrams illustrating the progress of the sheet through the press. Fig. 6 is a cross-section of part of the cylinder, showing the means for operating the grippers; and Fig. 7 is a diagram in larger size, showing in elevation and partial section the belts and pulleys, switch, and actuating-cam.

In my press there are many parts which, separately considered, are old and well known, and the details of construction and operation are not set forth herein, because they are of any ordinary character, and press-makers can supply the same without further information than that contained herein.

The roll of paper *a* is upon an arbor supported in a frame, *a'*. The paper passes up over the pressure feed-roller *b* and down be-

tween that and the female cutting-cylinder *c*, around the side thereof next to the roll *a*, thence between *c* and the male cutting-cylinder *d*, and up between the accelerating-belts *e e'* (shown by dotted lines,) over the breaking or nipping roller *d'*, and then descends between the belts or tapes *e e'* as they pass down. The cylinders *c* and *d* are driven by bevel and toothed wheels actuated from the main driving-shaft, as shown, or in any other convenient manner. The endless tapes or belts *e* pass below the roller 1, above the roller 2, below the roller 3, thence around the roller 4, below the roller 5, over the nipping-roller *d'*, and down to and below roller 1. The endless belts or tapes *e'* pass over the nipping-roller *d'*, down to and below rollers 6 and 7, over and around the roller 8, down to and below the rollers 9 and 10, up to and over nipping-roller *d'*; hence the belts *e* and *e'* are contiguous and at opposite sides of the paper from the roller 1, up to and over the nipping-roller *d'*, and down to the roller 5.

There is an endless belt or tapes, *e³*, passing around the roller 7, beneath the roller 6, up over the roller 12, down below 13, and to 7. There is another endless belt or tapes, *e'*, around the rollers 14 and 15. The axis of the roller 6 is secured in adjustable sliding bearings, (see Fig. 7,) and said bearings are secured to the frame of the machine and held in place by set-screws or bolts in the usual manner; and by adjusting the roller 6 the proper tension is given to the tapes *e* and *e³*, and the tape *e'* is brought nearer to or farther from the rollers 5 and 12.

The male and female cutters on the cylinders *d c* are of the usual character, having points that penetrate the paper, but do not entirely separate the web; hence after the paper is cut it is carried up against the belt *e'*, then between *c* and *e'*. The belts travel faster than the paper, but the sheet does not receive the speed of the belts until its advancing end reaches the nipping-cylinder *d'*, and passing around the same it is pulled upon and entirely separated from the web. The advancing end of the sheet, however, is drawn forward between the belts *e e'* as fast as the cylinders *c* and *d* are traveling, and this operation effects a separation of one sheet from the

other and carries the separated sheet along faster than the advancing end of the web of paper and produces a space between one sheet and the next. As the sheet of paper passes over the roller d' , it descends between the tapes $e' e'$. A switch, f , (see Figs. 1 and 7,) is used to deflect every alternate sheet from the tapes $e' e'$ in between the tapes $e' e'$, and when in the position shown in full lines, Fig. 7, said switch f deflects the sheet in this way. In the position shown by dotted lines, Fig. 7, the switch f allows the sheet of paper to continue its downward journey and pass between the tapes e' and e' , and be by them carried around the roller 6 and onward to a position near the roller 8, where it is grasped by the grippers on the impression-cylinder h . This switch f is operated by any suitable means. I have shown a rock-shaft, 50, and a rod to a cam, 51, upon the shaft of the cylinder r .

The switch at f is of ordinary character—such as is used in printing-presses—and the same does not form any part of my invention; and as the impression-cylinders h and h' are made in the same manner and the devices hereinafter described are duplicated, it is not necessary to describe the parts used with the cylinder h' ; and I further remark that where the press is supplied with paper from a second roll there are to be cylinders h^2 and h^3 , with all the parts duplicated, at the other side of the press, or with equivalents of said parts.

The main cylinder D is divided into two parts. The surface shown at the left side at l is a table for ink-distribution. At m are the types that give the first impression, and at n the types that give the second impression. The circumference of this cylinder D is equal to the length of four sheets of paper plus the distance between the separated sheets, and presuming that the cylinder D is revolving in the direction shown in Fig. 1 by the arrows, the sheet to be printed reaches the grippers 28 and is taken by them to the cylinder, so that it receives an impression from the types m . Then the inking-table l passes the cylinder h , and during the half-revolution of D the sheet of paper that has received one impression from m is reversed and brought back by the cylinder h and receives the second impression from the types n , and by the time the cylinder D has moved around, so that the types m again reach the cylinder h , there is another sheet ready to be impressed by the said types m .

The inking-rollers o are of any suitable character. They are in groups at o', o^2, o^3 , and o^4 , and they are upon slides in the main frame. These slides are provided with rollers that are in contact with the cam o^5 , that revolves with the cylinder D ; hence the inking-rollers are raised for the types to pass below and in contact with the inking-rollers, and then drawn inwardly by springs. (See Fig. 1.) Said springs surround the slides and bear between the frame of the machine and a boss on the slides, and they act to press the rollers inwardly and cause them to bear either upon the ink-distributing

table or upon the types. The ink-table is nearer the center of the cylinder D than the surface of the types; hence such ink-table does not come into contact with the impression-cylinders.

The ink-fountain p , ink distributing cylinder p' , working-rollers p^2 , and transfer-roller p^3 , that spreads the ink upon the ink-table l , are all of ordinary character. This transfer-roller p^3 may be operated in any well-known way to bring it alternately into contact with the inking-table or distributing-cylinder.

I will now describe the special construction of the impression-cylinder h and transfer-cylinder r . Each of these cylinders is half the diameter of the cylinder D , and hence half the circumference of the cylinder h or r is equal to a quarter of that of the cylinder D , and corresponds, or nearly so, to the length of paper that is to be printed.

28 is a gripper that is opened by a stationary cam at 40 and allowed to spring and close upon the advancing edge of the sheet as it is carried up by the belts e' and e^3 . As the half h^4 of the cylinder h rolls in contact with the types m , the sheet of paper upon the said half h^4 receives its first impression. As the grippers 28 reach the point of contact with the transfer-cylinder r , the grippers 29 of said transfer-cylinder arrive at the same place, are opened by a stationary cam 43, (see Fig. 2,) and close upon the advancing edge of the sheet at the same moment that the grippers 28 are released by a stationary cam 44. The grippers 29 now hold the sheet, and as the cylinders h and r revolve said sheet is transferred from cylinder h to cylinder r ; but the last end of the sheet comes even with the position of the grippers 31, and as the cylinders move into the position shown in Fig. 4 a stationary cam 45 opens the grippers 31, and at the same moment the tucking-blade 30 on cylinder r is pushed forward by a stationary cam 46, carrying the edge of the paper into the grippers 31, and they grasp the said last end of the sheet; and at the same instant the grippers 29 are opened by a stationary cam 47, and yield the sheet to the grippers 31, to be carried by them back again upon the impression-cylinder h with the still unprinted surface to the types. Fig. 3 represents the position of the parts when the advancing end of the sheet is taken by the grippers 29 and dropped by the grippers 28, and Fig. 4 shows the position of the parts when the rear end of the sheet is taken by the grippers 31 and dropped by the grippers 29, ready to be carried back for the second impression. By the time the grippers 31 arrive at the types the advancing end of the types n have reached the same place and the second impression is given by them, and when the grippers 28 reach the belts $e' e^3$ there is a second sheet ready to be taken by said grippers to receive the first impression. The first sheet, when receiving the second impression, is upon the half h^5 of the cylinder h and the center of the sheet is across the tucking-blade 32, which tucking-blade 32 at

the proper time, and by action of stationary cam 48, presses the middle of the sheet into the grippers 33 on the transfer-cylinder *r*. These grippers 33 are opened by the stationary cam 49 and closed by a spring, and they carry off the sheet with one fold in it, because the grippers 31 drop the advancing end of the sheet as the middle is pressed into 33. The tucking-blades 30 and 32 are operated by the cams 46 and 48, and are returned by the springs shown in Fig. 2 by dotted lines. In Fig. 6 I have shown the spring employed for closing and holding the grippers. It surrounds one end of the gripper-shaft outside the cylinder. One end of the spring is secured to the cylinder and the other end to a boss secured to the shaft. This construction is commonly employed.

There are endless tapes *t* passing around the cylinder *r*, over the roller 34, and around the roller 35, the tucking-blade 30 being notched at the places occupied by such belts, and the grippers being located so as to be clear of such belts. The cylinder *r* is also to be recessed for the tapes, so that they are below the level of the groove into which the tucking-blade 32 enters. There are also endless tapes or belts *u* around the rollers 34 and 36, and at the moment when the grippers 33 reach the roller 34 they are opened, so that the advancing fold of the paper is carried in between the belts *t* and *u*, over the roller 34, and forward to a position underneath the tucking blade *v*. The tucking-blade *v* then forces the sheet into the bite of the revolving rollers *v'*. The sheet then passes from these rollers downward before the fly *w*. This fly lays the sheet upon the table *x*. This table is supported upon four springs, which yield under the weight of the folded paper, so that the height of the pile of the paper will be relatively the same to the fly *w*.

As the paper-folding machine is a well-known appliance in printing-presses, and the various grippers employed by me being also well known, it is unnecessary to describe these in detail or to represent all the devices for operating the same. I remark, however, that the grippers 28 need only operate every second revolution, because there will not be a sheet to be taken at the time the inking-table of *D* is passing by the impression-cylinder. The blade 30 and grippers 31 will only act every other revolution. So, also, the transfer-grippers 29 will operate every second revolution, because the sheet will be at the places to be acted upon each two revolutions. It is immaterial whether the parts go through their movements when there is not any sheet at the place, or whether the cams that open the grippers and move the tucking-blade are brought into action each two revolutions.

It is of course understood that the printing-cylinders and other parts of the machine are geared together, so as to rotate in their proper order.

The cutting-cylinders *c d* make two revolu-

tions to one of the cylinder *D*, and consequently deliver a sheet to each of the cylinders *h* and *h'*, as previously described.

When it is desired to operate but one printing-cylinder, the cutting-cylinders *c d* are geared to make one revolution to one of the cylinder *D*.

When it is desired to operate one of each set of impression-cylinders only, the other is thrown out of operation by removing its driving-gear and turning it around until the space where the grippers are placed comes opposite the type-cylinder.

I claim as my invention—

1. The combination, with the cylinder carrying two forms of type to print the two sides of paper, of an impression-cylinder with a circumference of about twice the length of the sheet to be printed, two sets of grippers upon the said cylinder, and a reversing-cylinder and grippers to take the sheet from one set of grippers on the impression-cylinder, reverse it, and deliver it to the second set of grippers upon the impression-cylinder, substantially as specified.

2. In combination with the printing-cylinder *D*, the impression-cylinder *h*, the two sets of grippers 28 and 31, the cylinder *r*, and the grippers 29 and tucking-blade 30, substantially as and for the purposes set forth.

3. In combination with the printing-cylinder *D*, the impression-cylinders *h*, carrying-grippers 28 and 31 and tucking-blade 32, and the cylinder *r*, carrying grippers 29 and 33 and tucking-blade 30, so that sheets of paper may be printed on both sides and folded at continuous operations, substantially as specified.

4. In a printing-press, the combination, with the impression and transfer cylinders, of the cutting-cylinders *c d*, nipping-roller *d'*, tapes *e* and *e'*, *e*² and *e'*², and their rollers, switch *f*, and adjustable roller 6, substantially as described, so that sheets may be separated and delivered to the two impression-cylinders, substantially as specified.

5. The cutting-cylinders, nipping-roller, and conveying-tapes, in combination with the type-cylinder, impression-cylinder, and transfer-cylinder, and folding mechanism, substantially as described, so that from a web of paper sheets may be cut and printed on both sides and folded automatically by continuous operations, substantially as specified.

6. In a printing-press, the combination, with the printing-cylinder *D*, having the types and an inking-table, and the impression-cylinders around the same, of a transfer-cylinder, *r*, accompanying and operating in connection with each impression-cylinder *h*, the feeding and cutting cylinders *c d*, the conveying-tapes and switch *f*, and actuating mechanism, substantially as specified, the parts being so constructed and operated that one or more sets of printing and transfer cylinders can be thrown out of action without affecting the remainder, substantially as specified.

7. The combination, with an impression-cylinder provided with a tucking-blade, of a second cylinder provided with grippers and co-operating with said tucking-blade, whereby the printed sheets are folded off from said impression-cylinder, substantially as described. 5
8. The combination, with an impression-cylinder provided with sheet-seizing devices, of a tucking-blade carried by said cylinder and adapted to fold the sheets therefrom after being printed, substantially as described. 10
9. The combination, with an impression-cylinder provided with a tucking-blade and co-operating with grippers carried by a second cylinder, whereby sheets are delivered after 15 being printed, once folded, to said second cylinder, of a secondary folder, and means for directing the once-folded sheets from the sec-

ondary cylinder to the secondary folder, substantially as described. 20

10. The combination, with an impression-cylinder and a reversing-cylinder, each of which is provided with sheet-seizing devices, whereby a sheet printed upon one side is reversed and its unprinted side carried into position to be printed, of a member of a folding device carried by each cylinder and co-operating with each other, whereby the printed sheet is delivered from the impression-cylinder, once folded, substantially as described. 25

Signed by me this 19th day of June, A. D. 30
1882.

WALTER SCOTT.
